INVENTOR:
May W. Bixler

UNITED STATES PATENT OFFICE.

HENRY W. WINTER, OF METHUEN, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

POSITIONING DEVICE.

1,294,012.

Specification of Letters Patent.

Patented Feb. 11, 1919.

Application filed October 2, 1917. Serial No. 194,412.

To all whom it may concern:

Be it known that I, HENRY W. WINTER, a citizen of the United States, residing at Methuen, in the county of Essex and State 5 of Massachusetts, have invented certain Improvements in Positioning Devices, of which the following description, in connection with the accompanying drawings, is a specification, like reference characters on the drawings indicating like parts in the several 10 figures.

This invention concerns gaging devices for positioning work in some definite relation to an element which is to operate upon it. It 15 more particularly relates to gages for thus determining the positions of the soles of shoes.

A purpose of the invention is to provide an arrangement whereby objects varying in 20 two dimensions may be presented accurately to an operating element so that the operations will be performed, for example, at some predetermined distances from the margin. Conditions calling for the employment 25 of the invention are encountered, as an instance of its application, in stamping trade marks or other inscriptions upon the soles of shoes just at the inner side of the heel breast. As soles change in length from one 30 size to another, they change also in width, under the present practice the ratio between these variations being as four to one, since for a size the length differs from that preceding or succeeding it by one-third of an 35 inch, while at the same time the width varies one-twelfth of an inch.

With this object in view, a feature of the invention consists of gage members movable in directions corresponding to the longitudinal and transverse dimensions of objects to be gaged, this movement being effected 40 through distances having the same ratio as the dimensions of the objects.

Still another feature relates to the capability of adjustment of at least one of the gage members to adapt the device for variations in one dimension independently of those which attend or are controlled by variations in another dimension.

50 These features, together with others involved in the invention, will now be described in connection with the accompanying drawing, in which—

Figure 1 shows one form of my improved

positioning device applied to a stamping 55 machine;

Fig. 2 is a top plan view of the work table, parts being broken away, and

Fig. 3 is a section on the line 3—3 of Fig. 2. 60

The numeral 10 designates the form of a stamping machine in connection with which apparatus I have chosen to illustrate my invention, though it is to be understood that it may be applied to other types of machine. 65 In this frame operates a stamping head 12 movable above a table 14 for supporting the work, this work, in the present instance, consisting of the soles of shoes at the center of which, transversely, and just forward 70 of the heel portion an inscription is to be stamped. The sole is accurately positioned with respect to the dies 16 carried on the head, by gage members 18 and 20. The former member provides an end gage arranged to contact with the center of the heel end of the sole to bring the dies into contact with the desired points upon the sole, considered longitudinally. The member 20 serves as a side gage, and against this rests 75 the side of the heel portion of the sole, fixing its position to bring the inscription at the transverse center. Through the table from the rear forwardly is a slot 22 through 80 which extends the gage member 18, carried 85 by and preferably integral with a slide 24 situated below the table and mounted to move in ways furnished by plates 26, 26 secured to webs, cast upon the under side of the table by screws 28. The inner and upper corners of the plates 26 enter rectangular recesses in the outer edges of the slide 24 to permit said slide to be moved longitudinally of the table, that is, from the front to the rear or the reverse. At the forward side of 90 the table is a depending lug 30 threaded to receive an actuating member for the slide 24, which may consist of a screw 32 held against longitudinal movement by engagement of the inner side of its head 34 with a 100 boss 36 upon the frame, the inner side of the boss contacting with a collar 38 which may be integral with the screw. The boss is slotted vertically to enable the screw 32 to be introduced into the opening in the 105 frame.

At the upper side of the slide 24 is a projection 40, preferably in the form of a rec-

tangular bar, integral with the slide and being inclined at an angle to the direction of movement of the slide. Between the slide 24 and the under side of the table is located 5 a transverse slide 42 movable substantially at right angles to the direction of movement of the first-named slide in ways furnished by a slot 44 formed beneath the table. This projection 40 enters a similarly inclined angular depression 46 in the under side of the slide 42. The table is slotted transversely at 48, and through this opening projects a raised portion 50 of the slide 42. Upon the portion 50, guided by a 10 square boss 52 entering a slot 54 in the horizontal portion 55, is the side gage 20. This side gage may be adjusted independently of the end gage 18 by moving it upon its slide 42, by virtue of the slotted connection with 15 the boss 52, and clamped in the desired position by a screw 56 threaded into the boss and having its head contacting with the horizontal portion of the gage.

The operator in using this gaging device 20 alters the position of the end gage 18 by turning the screw 32 in one direction or the other, until, when the sole to be stamped is in contact with said gage, the inscription will be at the proper point longitudinally 25 of the sole. In thus shifting the end gage, its projection 40, moving through the depression 46, by virtue of its inclination shifts the slide 42 transversely so that the side gage is simultaneously moved toward or from the 30 side of the sole. The angle of inclination of the elements 40 and 46 is such that this latter movement is in the correct ratio of the difference between the lengths of diverse sizes to the difference between the widths of such 35 sizes, this being, as already stated, customarily as four to one. Obviously, however, within reasonable limits the inclination of the parts could be changed to give any other ratio necessary. The side gage having been 40 given a proper initial setting by the screw 56, this will maintain the inscription always in the correct central position transversely of the sole. Thus it will be seen that for all 45 variations in the size of the soles they may be accurately positioned by a single actuating element. If the width changes, as well as the size, this is provided for by an adjustment of the side gage through the 50 screw 56.

Having thus described my invention, what I claim as new and desire to secure by Letters Patent of the United States is:

1. A device for positioning objects in 60 which longitudinal and transverse dimensions vary in accordance with a definite ratio, comprising gage members movable respectively in corresponding longitudinal and transverse directions, and means constructed 65 and arranged for moving said members

through distances having the same ratio as the dimensions of the object.

2. A device for positioning objects in which longitudinal and transverse dimensions vary in accordance with a definite ratio, 70 comprising gage members movable respectively in corresponding longitudinal and transverse directions, means constructed and arranged for moving one of said members, and connections between the member moved 75 and the other member for moving the latter, the relative movement of the members being in the same ratio as the dimensions of the objects.

3. A device for positioning portions of 80 shoes comprising end and side gage members, and means for moving said members simultaneously to points the relations of which are determined by the ratio of the length and width of a shoe. 85

4. A device for positioning portions of shoes comprising end and side gage members, means for moving one of said gages, and means controlled by said moving means 90 for moving the other gage to a point determined by the ratio of the length and width of a shoe.

5. A device for positioning portions of shoes comprising end and side gage members, 95 means for moving one of said gages, means controlled by said moving means for moving the other gage to a point determined by the ratio of the length and width of a shoe to symmetrically position the work 100 when one of these dimensions changes, and means for fixing one of the gages in different initial positions to compensate for changes in the other dimensions.

6. In a machine for stamping upon the soles of shoes inscriptions in a predetermined 105 relation to the length and width of each sole, an end gage and a side gage for the soles, and means for moving the gages including connections between said gages operating to maintain for different sizes the desired relation of the inscriptions longitudinally and transversely of the soles. 110

7. A device for positioning the soles of shoes comprising a slide provided with a 115 projection, a second slide having a depression engaged by the projection, gages mounted upon the slides, and actuating means for moving one of the slides and thereby moving the other slide through the 120 agency of the projection and depression.

8. A device for positioning the soles of shoes comprising a slide provided with a projection, a second slide having a depression engaged by the projection, gages mounted upon the slides, and actuating means for moving one of the slides and thereby moving the other slide through the agency of the projection and depression, said 125 depression being inclined with respect to the 130

direction of movement produced by the actuating means.

9. A device for positioning the soles of shoes comprising a slide provided with a projection, a second slide having a depression engaged by the projection, gages mounted upon the slides, and actuating means for moving one of the slides and thereby moving the other slide through the agency of the projection and depression, said depression being inclined with respect to the direction of movement produced by the actuating means and the angle of inclination being determined by the ratio of the difference between the lengths of diverse sizes of soles to the difference between the widths of such sizes.
10. In combination, a work table having ways extending substantially at right angles to one another, slides movable in the ways, 20 to one another, slides movable in the ways,
11. In combination, a work table having ways extending substantially at right angles to one another, slides movable in the ways, said slides being provided with a coöperating projection and depression inclined to the direction of movement, gages mounted upon the slides, and a screw rotatable in the table and engaging a thread in one of the slides.
12. In combination, a work table having ways extending substantially at right angles to one another, slides movable in the ways, 30 said slides being provided with a coöperating projection and depression inclined to the direction of movement, gages mounted upon the slides, one of the gages having a slot and a screw passing through the slot to secure the gage to the slide, and a screw rotatable in the table and engaging a thread in one of the slides.

In testimony whereof I have signed my name to this specification.

HENRY W. WINTER.
